GAUGE PIN

William A. Hoover, Pittsburgh, Pa.

Application April 5, 1939, Serial No. 266,188

5 Claims. (Cl. 101—415)

This invention relates to an improved gauge pin adapted to be removably applied to the tympan sheets of printing presses for locating the sheet to be printed.

It is a primary aim of this invention to provide an improved gauge pin of simple construction including an abutment surface including a smooth uninterrupted portion adapted to be engaged by the sheet to be printed.

Still a further aim of the invention is to provide improved means for attaching the gauge pin to the tympan sheet and for slidably connecting the slide to the base portion of the pin.

Other objects and advantages of the invention will hereinafter become more fully apparent from the following description of the drawing, which illustrates a preferred embodiment thereof, and wherein:

Figure 1 is a top plan view of the gauge pin,
Figure 2 is a side elevational view of the same.

Figure 3 is an end view in elevation looking toward the abutment surface.

Figure 4 is a longitudinal vertical sectional view taken along the line 4—4 of Figure 1.

Figure 5 is a plan view of the blank from which the base portion of the pin is formed, and

Figure 6 is a corresponding view of the blank from which the slide is formed.

Referring more particularly to the drawing, wherein like reference characters designate like or corresponding parts throughout the different views, 10 designates generally the gauge pin which includes the base and slide designated generally 11 and 12, respectively.

Base 11, as best seen in Figure 5, is formed from a single blank of relatively resilient metal and including a head or plate 13 provided with the spaced longitudinally disposed slots 14 intermediate of its ends. Plate 13 adjacent one of its longitudinal edges is elongated to form the flanges 15 and said edge is likewise provided with projecting prongs 16. The strip between the slots 14, designated 17, is scored at the end of one of the slots 14 as indicated at 18, for a purpose which will hereinafter be described. Formed integral with and projecting from the opposite longitudinal edge of plate 13 are the corresponding blades 19 having the undulating free ends 20 as seen in Figures 1 and 2. Disposed between the blades 19 is a blade 21 which is spaced from blades 19 and which is provided with a pointed end 22 which extends beyond the ends 20 and which is bent upwardly.

As best seen in Figures 2 and 4, plate 13 is bent longitudinally through the strip 17 to form the

abutment surface 23 which is disposed substantially at right angles to the blades 19 and 21 and from which depends the prongs 16. Depending obliquely from the upper edge of the abutment surface 23 is a diagonally disposed portion 24. One of the slots 14 is disposed in the surface 23 while the other slot 14 is positioned in the portion 24 and in alignment with the first mentioned slot, as seen in Figure 4. The scored portion 18 enables the forward edge 25 of the strip 17 to 10 project outwardly over the abutment surface 23 above its slot 14, as best seen in Figure 4.

The slide 12 is likewise formed of a single strip of thin relatively flexible metal and includes a body portion 26 having at each end thereof a 15 pair of corresponding spaced outwardly projecting ears 27. A tongue 28 projects from one side of the base 26 and a lip 29 projects upwardly from the opposite side thereof.

Slide 12 is adapted to be slidably connected to 20 the base 11 by positioning the body portion 26 above the blade 21 with the ears 27 in each end thereof engaging above and beneath each of the blades 19, as seen in Figure 1, and with the tongue 28 projecting through the aligned slots 14. 25 The ears 27 enable the member 12 to be moved longitudinally of the base 11 and yet provided sufficient frictional engagement with the blades 19 to prevent casual movement of the slide 12. The free end of the tongue 28 is inclined upwardly as indicated at 30 while its intermediate portion is bowed upwardly as seen at 31. The flanges 15 are bent to project rearwardly or toward the portion 24, as best seen in Figure 1, to provide rounded ends for the abutment surface 35 23.

The gauge pin 10 is adapted to be applied to a tympan sheet, not shown, by causing the pointed end 22 to pierce the sheet at spaced points so that its intermediate portion is disposed beneath the sheet and its ends above the sheet to locate the base 11 relatively thereto and when thus properly adjusted plate 13 may be pressed downwardly to cause the prongs 16 to pierce the platen, not shown. A plurality of gauge pins 10 may be applied to the tympan sheet to be engaged by two edges of a sheet to be printed, not shown, to definitely locate and position said sheet relatively to the tympan sheet. In using the pin it is necessary that the projecting end of the tongue 40 28 shall be either close to the platen or remote therefrom, depending on the nature of the work to be printed. As the metal of the tongue 28 is 45 substantially ductile its projecting end portion may be shaped or moved inwardly towards the 50 55

platen or arranged remote therefrom as desired and will hold the position to which fashioned. By having the end of the tongue close to the platen the pin will be best adapted for close register work and for curled paper to insure that the curled edges of sheets to be printed will engage under the end 30 to be directed thereby against the abutment surface 23, which constitutes the front of the gauge pin 10 and which is 5 adapted to hold the sheet in position for printing. When the gauge pin 10 is in position for use the bottom free edge of the abutment surface 23 is resting on the tympan sheet to form a smooth substantially flat outwardly projecting 10 surface for engaging a sheet to be printed. The blade 21 is bent to project upwardly relatively to the blades 19 so that it will frictionally engage the under side of the body portion 26 to more effectively prevent casual movement of the slide 15 12. The lip 29 forms a finger grip by means of which slide 12 is adapted to be moved longitudinally of base 11 for adjusting the angle and length of the end 30 of the tongue 28.

Various modifications and changes in the precise construction and arrangement of the parts forming the pin are contemplated and may obviously be resorted to, and the right is therefor expressly reserved to make such variations and changes as fall within the spirit and scope of the 20 invention as hereinafter defined by the appended claims.

I claim as my invention:

1. A device of the class described comprising a base member including a head, a plurality of blades projecting from one edge thereof and disposed in spaced apart relationship relatively to each other, one of said blades being elongated and terminating in a point, said head being provided with spaced longitudinal slots, said head being bent upwardly, adjacent said first mentioned edge, back upon itself and between said slots for disposing the slots in alignment with each other, prongs projecting from the opposite free edge of said head portion; a slide including a base portion provided with outwardly projecting ears, at each end, for engaging above and beneath certain of said blades for slidably connecting said portion to the base, and a tongue 25

projecting from said portion and extending through the aligned slots.

2. A gauge pin including a base having a plurality of spaced substantially parallel blades, a head at one end of said base, said head having an upwardly projecting portion bent back upon itself to provide an abutment surface, said head being provided with aligned slots, a slide including a body portion having outwardly projecting ears at each end to engage above and beneath certain of said blades, and a tongue extending from said body portion through the aligned slots. 10

3. A gauge pin comprising a base member including a plate bent to provide an abutment surface and a downwardly inclined portion, said abutment surface and portion being provided with aligned slots, a plurality of spaced substantially parallel blades projecting obliquely from said portion and adapted to engage a tympan sheet; a slide including a body portion provided with 20 ears at each end for engaging above and beneath certain of said blades, and a tongue projecting therefrom and extending through the aligned slots. 15

4. A gauge pin comprising a base member including three spaced blades connected by a head portion, said head portion having spaced longitudinal slots and being bent relatively to said blades to dispose said slots in alignment to provide an outer abutment surface disposed substantially at right angles to the blades, prongs depending from the bottom edge of said abutment surface; a slide including a body portion having pairs of outwardly projecting ears for engaging above and beneath the two outer blades, said 30 body portion being disposed above the intermediate blade, and a tongue projecting from said body portion and extending through the aligned slots. 25

5. A gauge pin including a base formed of a plurality of spaced substantially parallel blades 40 adapted to engage a tympan sheet, a head connecting said blades and including an abutment portion and an obliquely disposed portion depending from the upper edge thereof, said abutment and obliquely disposed portion having aligned 45 slots; and a slide including ears engaging above and beneath certain of said blades, and a tongue having its free end extending through said slots.

WILLIAM A. HOOVER.
